CLAIM

The ornamental design for an impeller blade for an agitator as shown and described.

DESCRIPTION

FIG. 1 is a front perspective view of an impeller blade for an agitator showing my new design, in which the double dot-dash line indicated by "9" designates the boundary of the enlarged view thereof shown in FIG. 9.

FIG. 2 is a rear perspective view thereof, in which the double dot-dash line indicated by "10" designates the boundary of the enlarged view thereof shown in FIG. 10.

FIG. 3 is a front elevational view thereof;

FIG. 4 is a rear elevational view thereof;

FIG. 5 is a left-side elevational view thereof;

FIG. 6 is a right-side elevational view thereof;

FIG. 7 is a top plan view thereof;

FIG. 8 is a bottom plan view thereof;

FIG. 9 is an enlarged view of the area 9 indicated by the double dot-dash broken lines in FIG. 1; and,

FIG. 10 is an enlarged view of the area 10 indicated by the double dot-dash broken lines in FIG. 2.

The double dot-dash broken lines in FIGS. 1, 2, 9 and 10 designate boundaries of the enlarged portions and form no part of the claimed design.
